UNITED STATES PATENT OFFICE.

LOUIS J. REICHEL, OF EAST DUBUQUE, ILLINOIS, ASSIGNOR OF ONE-HALF
TO THE TELEGRAPH JOB PRINTING COMPANY, OF DUBUQUE, IOWA.

DESK FOR HOTEL-REGISTERS.

SPECIFICATION forming part of Letters Patent No. 633,156, dated September 19, 1899.

Application filed March 27, 1899. Serial No. 710,575. (No model.)

To all whom it may concern:

Be it known that I, LOUIS J. REICHEL, a citizen of the United States, residing at East Dubuque, in the county of Jo Daviess and State 5 of Illinois, have invented certain new and useful Improvements in Desks for Hotel-Registers; and I do hereby declare the following to be a full, clear, and exact description of the invention, such as will enable others skilled in the art to which it appertains to make and use 10 the same.

My invention relates to hotel-register desks, with special reference to those upon which various advertisements are placed, and the 15 object is to provide a desk which shall have not only a convenient place for the register to rest upon, but also a place where advertisements can be displayed and kept clean and always in sight.

20 It consists of a turn-table upon which is placed a desk for holding the register and an advertising-case secured to the upper end of the desk and adapted to rest on one page of the register and also to be shifted from one 25 side to the other and rest upon the opposite page of the register.

It further consists in a removable heading for the register, upon which may be printed the name of the hotel, of the proprietor, and other 30 matter usually printed upon the heading of each page of hotel-registers, and made adjustable, so as to rest across the head of registers of different thickness.

In order to more fully explain the manner 35 in which my desk is constructed, its mode of operation, and how these objects with others of less moment are accomplished, attention is called to the following specification and drawings accompanying the same.

40 Figure 1 is a plan view of the desk, showing the advertisement-case resting upon one side of the desk. Fig. 2 is a side view of the desk with the advertising-case and head-plate closed down. Fig. 3 is a side view of the desk 45 with the advertising-case open and head-plate raised. Fig. 4 is a plan view of the under side of the desk, showing bottom of turn-table and mode of fastening the desk to the turn-table. Fig. 5 is a detail and enlarged view 50 of one side, showing part in section. Fig. 6 is a front view of the desk. Fig. 7 is a verti-

cal section of one of the standards for sustaining the rod to which the advertising-case is attached.

Like figures of reference denote corresponding parts in each of the drawings.

Referring to the drawings, 1 represents the base of the turn-table which rests upon legs 2. To this is pivoted the upper portion 4 of the turn-table by the pivot-pin 5. The plate 6 60 has a groove 6, running entirely around in the under side of the same, in which the balls 8 for the ball-bearing of the table travel. It will be seen by having the groove 6 only in the upper plate that there will be much less 65 friction in the turning of the table and also will prevent much of the noise consequent on the turning of the desk.

To the top of the plate 4 of the turn-table is securely fastened a desk 12 by the brackets 70 10 and 11. The brackets 10 being much longer than the brackets 11 will hold the desk at a convenient angle for writing, and as the brackets are secured to the plate 4 of the desk 12 the desk 12 will always maintain the same 75 angle in whatever direction the desk may be turned. This desk 12 is preferably made of a single board covered with cloth or some other textile fabric, and around the outer edges of both sides and front may be secured 80 an ornamental molding 13, made of wood or metal.

At the opposite corners of the upper end of the desk 12 are fastened sockets 14 by bolting the arm 15 of the socket 14 to the under 85 side of the desk 12. Into these sockets 14 are removably placed the standards 16. (Shown in Fig. 7.) These standards are provided with holes 18 and 19. Into holes 18 are inserted, preferably, a square rod 20, having 90 rounded ends, so that it can be partially revolved, and to which the advertising-case 22 is loosely fastened in such a manner that it may be moved along upon the rod 20 between the two standards 16. The advertising-case 95 22 is made of a frame 23, of ornamented metal, about the length of a register to be used therewith and of the width of one page of the register. The under side of this frame 23 may be covered by a thin board or sheet 100 metal, or a mirror facing downward may form the back of the frame, and upon the same are

placed the sheets upon which advertisements are printed. For the purpose of keeping the advertisements clean and free from blots a glass is placed above them. This case is attached to the rod 20 by the loops 28. In the hole 19 is inserted a rod 30, to which is rigidly attached the head-plate 31. For the purpose of raising the head-plate 31 whenever the advertising-case 22 is raised, there is attached to one end of the rod 30 a hook 33, and to the rod 20 is rigidly attached another hook 35, and as the show-case 22 is raised the rod 20 will be turned and will force the hook 35 into an engagement with the hook 33 and raise the head-plate 31, as shown in Fig. 3.

The manner of using my device is substantially as follows: Starting with the desk, as shown in Fig. 2, the operator raises the case 22, and the hook 35 engages with the hook 33 and lifts the head-plate 31 until it has the appearance shown in Fig. 3. The open register, which may be any form of blank book conveniently ruled for that purpose, is placed upon the desk 12, with its upper end against or near the rod 20. It will be remembered that as the standards 16 are loosely inserted in the sockets 14 they will readily adapt the plate 31 and the case 22 to registers of different thicknesses and both rest upon the register when they are closed down. The operator then closes down the case 22 until it rests upon and covers one page, say the right page, of the register, leaving the other half for the registration of names of the guests. At the same time if the case 22 is lowered the head-plate 31 will also be lowered and rest upon the upper end of the book. Upon this head-plate is impressed the name of the hotel and the proprietor thereof and all other printed matter usual upon the head of each page of a register and when it is closed down upon the register will represent the appearance of the top or head of the register having the names of the hotel and the proprietor, &c., thereon. It will be seen by having impressed upon the head-plate the above that it will serve for all registers without any cost of printing upon the upper end of each page of the register. When the left-hand page is filled with the names of guests, the case 22 is raised and shoved along on the rod 20 until it reaches the plate 16 of the right-hand side and then is lowered to rest upon the left-hand page of the register, leaving the right-hand page free to be registered upon. In this way the advertisements placed upon the case 22 will always be either upon one page of the register or the other and always in sight.

Whenever there is a desire to have a change in the advertising, the glass can be removed and a new advertising-sheet placed in the frame of the case 22 and the glass reinstated.

Having now described my invention, what

I claim, and desire to secure by Letters Patent, is—

65

1. In a desk for hotel-registers, a desk, a rod adjustably attached to the upper end of the desk, and an advertising-case loosely attached to said rod and adapted to be shifted from one side to the other of the desk, as and for the purposes shown.

70

2. In a desk for hotel-registers, a desk, sockets attached to the opposite corners of the upper end of the desk, standards adjustably fitting into said sockets, a rod uniting said standards and an advertising-case loosely attached to said rod, whereby the case can be shifted along said rod from one side to the other of the desk, as and for the purposes shown.

75

3. In a desk for hotel-registers, a desk, a head-plate adjustably attached to the upper end of the desk, and an advertising-case adjustably attached to the upper end of the desk, and adapted to be shifted from one side to the other of the desk as and for the purposes shown.

80

4. A desk for hotel-registers, consisting of a turn-table, a desk attached to the turn-table, and an advertising-case attached to the upper end of the desk and adapted to be shifted from one side to the other of the desk.

85

5. A desk for hotel-registers, consisting of a turn-table, a desk attached upon said turn-table, and a head-plate adjustably attached to the upper end of the desk, and adapted to rest on the upper end of open registers of different thicknesses, as and for the purposes shown.

90

6. A desk for hotel-registers, consisting of a turn-table having ball-bearings, a desk secured at an angle to said turn-table, a head-plate adjustably attached to the upper end of said desk, and an advertising-case adjustably attached to the upper end of the said desk and adapted to be shifted from one side to the other of the desk, as and for the purposes shown.

95

7. A desk for hotel-registers, consisting of a turn-table, the upper plate of which is grooved on its underside, ball-bearings traveling in said groove and upon the lower plate, a desk secured at an angle to said turn-table, a head-plate adjustably attached to the end of the said desk, sockets in the corners of said desks, standards in said sockets, a rod connecting said standards, and an advertising-case loosely fastened to the rod and adapted to be shifted from one side to the other of the desk, as and for the purposes shown.

100

In testimony whereof I affix my signature in the presence of two witnesses.
